UNITED STATES PATENT OFFICE

2,447,216

TRACK TOOL

John L. Tidwell, Homedale, Idaho

Application August 13, 1947, Serial No. 768,388

4 Claims. (Cl. 104—13)

1

The present invention relates to track tools and it consists in the combinations, constructions and arrangements of parts herein described and claimed.

It is an object of the invention to provide a tool for placing ballast beneath the ties of a railroad track.

Another object of the invention is the provision of automatic means and mechanism for withdrawing the tool referred to after its load of ballast has been positioned.

A further object of the invention is the provision of a novel scale which may be incorporated into a device of the character set forth.

A still further object of the invention is the provision of a track tool which while inexpensive to manufacture and simple in its operation, is nevertheless efficient and effective in its use.

Other and further objects of the invention will become apparent from a reading of the following specification taken in conjunction with the drawing, in which:

Figure 1 is a side elevational view of an embodiment of the invention, and

Figure 2 is a plan view thereof.

Generally there is provided a tool for placing ballast beneath the ties of a railroad track and including an elongated pan having a plurality of steps upon its upper side and provided with a scale at its forward end with which to measure the height of ballast needed and a scale upon its side for measuring the depth of ballast necessary to fill in the space beneath the tie. A framework is provided with operating handles and a ram which is normally spring-pressed in a forward direction but which may be forced backward when the apparatus is thrust beneath the tie and which then causes a quick retraction of the pan from the tie when the force of the thrust is expended.

Referring now more particularly to the drawing, there is shown therein a track tool having an elongated pan 10 which is slightly tapered toward the forward end 11 thereof. The pan is provided with upright sides 12 and an end wall 13 interconnects the rear ends of the sides 12. The upper face of the pan is provided with a plurality of steps 14.

Adjacent the forward end 11 of the pan, one side 12 is provided with a linear scale 15 and to one of the sides, at a point adjacent the rear thereof, there is affixed an upwardly extending arm 16 having a linear scale 17 thereon.

A framework 18 consisting, preferably of a single piece of metal, is affixed to the rear of

2

the pan by means of rivets 19 or the like and extends rearwardly to form a vertical portion 20 and thence forwardly to form a bracket 21 having a dependant arm 22. A brace 23 interconnects the bracket portion 21 and the lower portion of the frame 18.

A ram is provided and consists of a horizontal shaft 24 reciprocally mounted in the vertical portion 20 and the arm 22. The shaft 24 carries a detent 25 at its forward end. Centrally of the arm 22 and vertical portion 20 the shaft is threaded as indicated at 27 and a nut 28 is threaded thereon and a washer 29 is mounted next to the nut upon its rear side. A compression spring 30 surrounds the shaft between the vertical portion 20 and the washer 29 and is adapted to urge the shaft in a forward direction.

A thrust handle 31 is affixed at the rear of the bracket 21 by means of rivets 32 or the like and a guiding handle 33 is carried by an upright bracket 34 likewise affixed adjacent the forward end of the bracket.

A detent 35 is pivotally mounted to the arm 22 as indicated at 36 and is provided with a forked free end 37. A latch member 38 having a handle 39 is pivotally connected to the bracket 34.

In operation, it will be apparent that a railroad tie 40 having a rail 41 thereon may first be lifted by means of a pick or jacks and that thereafter the scale 15, while the pan is held in a vertical position may be used to determine the height of ballast 42 necessary to fill in the space formed by the lifting of the track. The pan is then filled with ballast to the level needed, the scale 17 now being used to make this measurement.

The pan is then thrust beneath the tie 40 using the handles 31 and 33, the steps 14 preventing the ballast from sliding rearwardly during this operation. The forward thrust of the pan will bring the head 26 of the ram against the tie 40 causing the same to move rearwardly against the action of the spring 30. When the force of the thrust is expended, which will be immediately, the spring will react to again assume its normal position. This will cause the pan to automatically be removed with a violent motion from beneath the tie. Through inertia the ballast 42 will remain in position and the steps 14 will offer little resistance as they are inclined upwardly and forwardly.

If desired, the detent 35 may be dropped into position with its forked head 37 upon the shaft 24. In such position, the head 26 of the ram will be prevented from moving rearwardly and the

ram may now be used to impart blows upon the tie 40 to dislodge any ballast still remaining in the pan. This is especially effective where the track must be raised from one to six inches, as the solid impact throws the ballast to the center of the track.

While but one form of the invention has been shown and described herein, it will be readily apparent to those skilled in the art that many minor modifications may be made without departing from the spirit of the invention or the appended claims.

What is claimed is:

1. A device of the character described comprising an elongated pan, a framework associated with the pan, a thrust handle carried by the framework, a guide handle carried by the framework, a ram carried by said framework and adapted to engage a railroad tie when the pan is placed thereunder said ram comprising a horizontal shaft reciprocally mounted in said framework, a head for said shaft and a spring adapted to urge said shaft in a direction toward the open end of said pan.

2. A device of the character described comprising an elongated pan, a framework associated with the pan, a thrust handle carried by the framework, a guide handle carried by the framework, a ram carried by said framework and adapted to engage a railroad tie when the pan is placed thereunder said ram comprising a horizontal shaft reciprocally mounted in said framework, a head for said shaft, a spring adapted to urge said shaft in a direction toward the open end

of said pan and a detent adapted to engage said head whereby to render the spring inoperative.

3. A device of the character described comprising an elongated pan, a framework associated with the pan, a thrust handle carried by the framework, a guide handle carried by the framework, a ram carried by said framework and adapted to engage a railroad tie when the pan is placed thereunder said ram comprising a horizontal shaft reciprocally mounted in said framework, a head for said shaft, a spring adapted to urge said shaft in a direction toward the open end of said pan, a detent adapted to engage said head whereby to render the spring inoperative, and a latch to hold said detent out of engagement with said head.

4. A device as defined in claim 1 wherein the upper face of the pan is provided with a series of stepped portions extending downwardly and rearwardly.
